MANICURING APPARATUS

George S. Ubelhart, Lakewood, and John E. McAllister, Cleveland, Ohio, assignors to Vivian Beauty Shoppe, Inc., Cleveland, Ohio, a corporation of Ohio

Application August 31, 1933, Serial No. 687,600

19 Claims. (Cl. 132—74)

This invention relates to an automatic manicuring device and has for its primary object to provide such a device which is simple in construction, efficient in operation, and inexpensive to manufacture.

A further object of the present invention resides in providing a manicuring device wherein the various instruments required are removable and interchangeable and are positively actuated by motive power.

A further object of the invention resides in imparting a reciprocatory movement to the various instruments of the device as distinguished from the so called rotary movement.

A further object of the invention resides in providing multi-sided instruments adapted to be removably supported in the device and replaceable in the event of excessive wear or damage.

With the objects above indicated and other objects hereinafter explained in view, the invention consists in the construction and combination of elements hereinafter described and claimed.

Referring to the drawing,

Fig. 1 is an elevational view of a manicuring device embodying the present invention;

Fig. 2 is a longitudinal sectional view of the chuck end of the device showing the details of the construction;

Fig. 3 is a cross sectional view taken on line 3—3 of Fig. 2 and on an enlarged scale;

Fig. 4 is a cross sectional view taken on line 4—4 of Fig. 2 and on an enlarged scale;

Figs. 5 to 10 inclusive are views of various instruments used with the device; and

Fig. 11 is a cross sectional view taken on line 11—11 of Fig. 2 and on an enlarged scale.

In the drawing, a manicuring device embodying the present invention is illustrated generally in Fig. 1 and consists of a housing 20 within which an instrument 21 is reciprocated through the instrumentality of a cable 22 having one end connected with the instrument 21 and the opposite end operatively connected with an eccentric 23 connected to the rotor of a motor 24, the details of which will be hereinafter more fully explained.

The motor 24 has trunnions which are rotatably mounted within the upper ends of yoke 25 and the latter has a depending extension rotatably supported in the upper end of an upright member 26 so that the motor 24 may have a universal movement within a range for which it is intended. A supporting member 27, which is preferably circular, also has a depending tubular extension which fits within the upper end of the upright member 26 and is secured against accidental disengage-

ment by a screw 28 or other retaining means. A handle 29 in the form of an inverted U has its ends secured to the supporting member 27 in any suitable manner and encircles the motor 24 and yoke 25, serving the additional purpose of a protection 5 for the motor in the event that the device should be upset.

The supporting member 27 has a recess surrounded by a depending flange 30 which is adapted to receive and support the housing 20 when not in use and diametrically opposite thereto is a similar recess having an upwardly extending flange 31 within which is disposed a portion of the cable 22 adjacent the eccentric 23. The lower end of the upright member 26 has a base 32 secured thereto in any suitable manner and upon which the stand is supported. An extension 33 is connected at one end to a wall plug 34 by which current is supplied to the motor 24, the opposite end of the extension 33 being connected in any well known manner with the motor 24 and with a control switch 35 mounted upon the supporting member 27. As the stand forms no part of the present invention it is believed that further description is unnecessary but reference may be had to the McAllister copending application relating to the stand, Serial No. 681,521, filed July 21, 1933.

The housing 20, shown more clearly in Fig. 2, is in the form of a tubular member and may be made of any suitable material which is light so that it may be easily handled by an operator. The front end of the housing 20 is closed by a plug 36 which fits within the end of the housing 20 and is provided with a laterally extending 35 circumferential flange 37 which abuts with a shoulder formed upon the inner surface of the housing 20. The outer end of the housing 20 is then bent inwardly at 38 to hold the plug 36 securely within the housing 20. The plug 36 is 40 provided with an outwardly extending reduced portion 39 for a purpose which will be later described.

The rear end of the housing 20 is exteriorly 45 screw threaded at 40 to receive an interiorly screw threaded cap 41 which is provided with an axial opening 42. A cylindrical member 43 has an enlarged portion 44 formed upon its inner end and which portion is adapted to fit within the adjacent end of the housing 20. A laterally extending circumferential flange 45 is also formed integral with the member 43 and positions the member 43 with respect to the housing 20 by engagement between the flange 45 and the end of the housing 20. The body portion of the member 50

43 extends into the opening 42 of the cap 41 and the member 43 is securely clamped in position by means of the cap 41. The member 43 also has an axial bore 46 for a purpose to be later described. A band of rubber 47 is placed about the cap 41 and is provided for the purpose of tending to maintain the housing securely within the flange 30 provided upon the stand, as previously referred to.

10 Slidably mounted within the housing 20 is a member 48 which has a cylindrical extension 49 formed integral at its forward end. This extension is slidably disposed within an axial bore 50 provided in the plug 36 and its free end extends 15 slightly beyond the end of the reduced portion 39. The cylindrical extension 49 also has an axial bore 51 extending rearwardly and communicating with a bore 52 of larger diameter provided in the rear end of the slidable member 48. The 20 slidable member 48 is provided with an upper slot 53 extending rearwardly from its forward end and a lower slot 54 also extending inwardly from its forward end. The lower slot 54 has a block 55 disposed therein and which block is provided 25 with an extension 56 adapted to project through an opening provided in the wall of the housing 20 and which is peened over or riveted so as to secure the block against displacement. This block cooperates with the slot 54 to permit the member 48 to slide longitudinally within the housing 20 but also to prevent any independent relative oscillatory movement of the member 48 about its axis. The cylindrical extension 49 adjacent the slot 53 is provided with a transversely extending 30 tapered opening 57 to receive a corresponding tapered detent 58. This detent is maintained in depressed position by means of a flat spring 59 which is looped at its central portion about a pin 60 the ends of which are supported within aligned 35 openings 61 provided in the wall of the slidable member 48 and shown more clearly in Fig. 3. One end of the spring 59 extends forwardly and engages the upper side of the detent 58, as shown in Fig. 2, while the opposite end extends rearwardly and is disposed within the slot 53 and in engagement with the end wall of the slot.

40 The slidable member 48 is interiorly screw threaded at 62 and receives the screw threaded end 63 of a cylindrical member 64. This member 45 64 is of slightly less diameter than the inner diameter of the housing 20 so that no frictional resistance is afforded to its reciprocatory movement. The member 64 is provided with an axial bore 65 and a transversely extending slot 66. A 50 transversely extending slot 67 of lesser width is also provided in the rear portion of the member 64 which slot receives the body portion of a bolt 68 while the slot 66 has disposed therein the head portion of the bolt 68. A pin 69 extends transversely above the body of the bolt 68 and has its ends secured within the member 64, as more clearly shown in Fig. 4, to thus prevent accidental displacement of the bolt 68. The free end of the bolt 68 is exteriorly screw threaded at 70 to receive one end of a coil spring 71, while the opposite end of the coil spring 71 is secured to a screw threaded extension 72 formed integral with a member 73 slidably disposed within the bore 46 provided in the member 43. This connection 60 acts as a snubber or cushion with respect to the movements of the slidable member 48. It will be noted also that the bolt 68 is permitted to have an oscillatory movement about its longitudinal axis independently of the member 64.

75 The rear end of the member 43 has a reduced

5 screw threaded extension 74 which receives an interiorly screw threaded cap 75 having an axial bore in the end wall thereof. A member 76 is rotatably supported within the member 43 by providing an extension 77 which is loosely disposed within the bore 46 of the member 43. The member 76 has a laterally extending circumferential flange 78 provided thereon which is adapted to abut with the end of the reduced screw threaded portion 74. Sufficient clearance is provided 10 between the flange 78 and the cap 75 to permit the member 76 to rotate relatively to the cap 75 when the latter is tightly assembled upon the end of the member 43. The member 76 extends outwardly through the bore in the end of the cap 15 75 and has an axial bore 79 provided therein. Disposed within this axial bore 79 is a cable 22 the sheath of which is rigidly secured to the member 76 by peening over or otherwise securing the inner end of the cable to the inner end of the member 76 as indicated at 80. This connection should be such that the sheath of the cable 22 and the member 76 are of substantial unitary construction. The operating wire 81 of the cable extends through the sheath beyond the member 20 25 76 and is rigidly connected to a screw threaded plug 82. This plug 82 is disposed within a screw threaded bore 83 provided in the adjacent end of the member 77. The operating wire 81, of course, is so formed with respect to the sheathing of the cable 22 that it may freely reciprocate within the sheathing and impart reciprocatory movement to the slidable member 48.

30 Any type of instrument may be employed in connection with this device, depending upon the 35 purposes for which the device is to be used but in Fig. 2 a file 84 is illustrated as one type of instrument. This file has at its inner end an enlarged circular portion 85 which is preferably knurled upon the outer surface. A shank 86 is 40 formed integral with the enlarged portion 85 and axially thereof and is adapted to be inserted within the bore 51 of the extension 49. At the rear end of the shank 86 is a tapered groove 87 extending transversely which is adapted to coat 45 with the spring pressed detent 58 so as to secure the instrument in proper position with respect to the housing 20. The free end of the shank 86 is tapered at 88 so that it may easily pass the depending end of the detent 58 when the shank 50 is being moved to its innermost position. The detent 58 has sufficient rigidity to prevent accidental disengagement of the instrument but is of such construction as to permit withdrawal of the instrument in the event that a change of instrument is desired. To prevent any tendency of relative oscillatory movement about the axis of the shank 86 with respect to the extension 49 an extension 89 is formed upon the enlarged portion 85 and is adapted to be disposed within a groove 60 55 provided in the adjacent end of the extension 49.

In Figs. 6 and 7 a buffer is disclosed, being one of the elements which is adapted for use in connection with the device, while in Fig. 8 a nail brush is illustrated and in Figs. 9 and 10 massaging implements are illustrated, indicating that the device has many uses.

65 In Fig. 5 the so-called "orange stick" is illustrated and this instrument might readily be formed with shanks similar to those already described and in which reciprocatory movement is imparted. However, it has been found from actual experiment that very little movement is required in connection with the use of the orange stick and, as it is desirable that no injury should 70 75

occur in connection with the use of the device, it has been found that the vibration which is set up during the operation of the device is sufficient for this purpose. Therefore a cup-shaped member 90 having a reduced extension 91 within which the orange stick 92 may be secured is adapted to fit over the reduced extension 39 provided upon the plug 36. This cup-shaped member 90 is made of substantially resilient material and is slotted at 93 so that a tension may be exerted upon the extension 39 to prevent accidental disengagement.

The opposite end of the operating wire 81 in the cable 22 is connected in any suitable manner to an eccentric which is contained within that portion of the housing 23 and has any suitable means for imparting a reciprocating movement to the operating wire 81. As a suitable connection of this type is commonly known it is not believed necessary to explain any specific connection.

While we have described the preferred embodiments of our invention it is to be understood that we are not to be limited to the precise details of construction and arrangement of parts just described but various changes and modifications may be made without departing from the spirit of the invention as defined by the appended claims.

Having thus described our invention, we claim:

1. A device of the character described comprising a housing, a chuck slidably mounted in said housing and adapted to receive and support an instrument projecting beyond one end of said housing, and a reciprocable member having one end connected to said chuck and having its other end extending outwardly beyond the opposite end of said housing.

2. A device of the character described comprising a housing, a chuck slidably mounted in said housing and adapted to receive and support an instrument projecting beyond one end of said housing, a reciprocable member having one end connected to said chuck and having its other end extending outwardly beyond the opposite end of said housing, and means operatively connected to the outer end of said member for reciprocating said member.

3. A device of the character described comprising a housing, a chuck slidably mounted in said housing and adapted to receive and support an instrument projecting beyond one end of said housing, a reciprocable member having one end connected to said chuck and having its other end extending outwardly beyond the opposite end of said housing, and motor operated means operatively connected to the outer end of said member for reciprocating said member.

4. A device of the character described comprising a housing, a chuck slidably mounted in said housing and adapted to receive and support an instrument, a cable having one end connected to said chuck and having its other end extending outwardly beyond the opposite end of said housing, and means operatively connected to the outer end of said cable for imparting reciprocatory movement thereto.

5. A device of the character described comprising a housing, a chuck slidably mounted in said housing and adapted to receive and support an instrument, a cable having one end flexibly connected to said chuck and having its other end extending outwardly beyond the opposite end of said housing, and means operatively connected to the outer end of said cable for imparting reciprocatory movement thereto.

6. A device of the character described comprising a housing, a chuck slidably mounted in said housing and adapted to receive and support an instrument, a cable having one end swivelly connected to said chuck and having its other end extending outwardly beyond the opposite end of said housing, and means operatively connected to the outer end of said cable for imparting reciprocatory movement thereto.

7. A device of the character described comprising a housing, a chuck slidably mounted in said housing, an instrument having a shank removably supported by said chuck, a reciprocable member having one end connected to said chuck and its other end extending outwardly beyond said housing, and power actuated means operatively connected with the outer end of said member for imparting reciprocatory movement thereto.

8. A device of the character described comprising a housing, a chuck slidably mounted in said housing, an instrument having a shank removably supported by said chuck, a reciprocable member having one end swivelly connected to said chuck and its other end extending outwardly beyond said housing, and power actuated means operatively connected with the outer end of said member for imparting reciprocatory movement thereto.

9. A device of the character described comprising a housing, a chuck slidably mounted in said housing, an instrument having a shank removably supported by said chuck, a reciprocable cable having one end connected to said chuck and its other end extending outwardly beyond said housing, and power actuated means operatively connected to the outer end of said cable for imparting reciprocatory movement thereto.

10. A device of the character described comprising a housing, a chuck slidably mounted in said housing, an instrument having a shank removably supported by said chuck, a reciprocable cable having one end connected to said chuck and its other end extending outwardly beyond said housing, a sheath surrounding said cable and having one end connected to said housing, and power actuated means operatively connected to the outer end of said cable for imparting reciprocatory movement thereto.

11. A device of the character described comprising a housing, a chuck slidably mounted in said housing, an instrument having a shank removably supported by said chuck, a reciprocable cable having one end connected to said chuck and its other end extending outwardly beyond said housing, a sheath surrounding said cable and having one end swivelly connected to said housing, and power actuated means operatively connected to the outer end of said cable for imparting reciprocatory movement thereto.

12. A device of the character described comprising a housing, a chuck slidably mounted in said housing, an instrument having a shank removably supported by said chuck, a reciprocable cable having one end swivelly connected to said chuck and its other end extending outwardly beyond said housing, a sheath surrounding said cable and having one end swivelly connected to said housing, and power actuated means operatively connected to the outer end of said cable for imparting reciprocatory movement thereto.

13. A device of the character described comprising a housing, a chuck slidably mounted in said housing, an instrument having a shank removably supported in said chuck, means for pre-

- venting relative movement between said instrument and said chuck, a cable having one end connected to said chuck and its other end extending outwardly beyond said housing, and means connected to the outer end of said cable for imparting reciprocatory movement thereto.
14. A device of the character described comprising a housing, a chuck slidably mounted in said housing, an instrument having a shank removably supported in said chuck, resilient means for preventing accidental disengagement between said shank and said chuck and its other end extending outwardly beyond said housing, a cable having one end connected to said chuck, and means connected to the outer end of said cable for imparting reciprocatory movement thereto.
15. A device of the character described comprising a housing, a chuck slidably mounted in said housing, an instrument having a shank removably supported in said chuck, resilient means for preventing accidental disengagement between said shank and said chuck, means for preventing relative oscillatory movement between said instrument and said chuck, a cable having one end connected to said chuck and its other end extending outwardly beyond said housing, and means connected to the outer end of said cable for imparting reciprocatory movement thereto.
16. A device of the character described comprising a housing, a member slidably mounted in said housing, an instrument mounted on said housing, a reciprocable cable having one end connected to said slidable member and its other end extending outwardly beyond said housing, and means connected to the outer end of said cable for imparting reciprocatory movement thereto.

cable for imparting reciprocatory movement thereto to thereby cause said housing to be vibrated.

17. A device of the character described comprising a housing, a member slidably mounted in said housing, an instrument mounted on said housing, a reciprocable cable having one end connected to said slidale member and its other end extending outwardly beyond said housing, and motor actuated means connected to the outer end of said cable for imparting reciprocatory movement thereto to thereby cause said housing to be vibrated.

18. A device of the character described comprising a housing, a chuck slidably mounted in said housing and adapted to receive and support an instrument, a member connected to said chuck and reciprocable along its longitudinal axis, said member having its other end extending outwardly beyond said housing and means operatively connected to the outer end of said member for imparting reciprocatory movement to said member.

19. A device of the character described comprising a housing, a chuck slidably mounted in said housing and adapted to receive and support an instrument which projects beyond one end of said housing, motor operating means remote with respect to said chuck, and a flexible shaft operatively connected with said chuck and said motor operating means to be reciprocated by the said means and to cause reciprocatory sliding movement of said chuck.

GEORGE S. UBELHART, 35
JOHN E. McALLISTER.
